HERBERT E. METCALF, OF SAN LEANDRO, CALIFORNIA, ASSIGNOR TO THE MAGNAVOX CO., OF OAKLAND, CALIFORNIA, A CORPORATION OF ARIZONA.

METHOD OF EXHAUSTING VACUUM TUBES.

Application filed October 13, 1924. Serial No. 743,388.

The common practice among those skilled in the art of exhausting vacuum tubes is to heat the electrodes contained therein while under a high vacuum, such heating being of considerable assistance in exhausting the tube. This is customarily done by means of eddy currents applied from outside the tube or vessel. This heating of the electrodes is also used to vaporize various chemicals known as "getters", inside the vessel. The heating of the internal electrodes is said to free said electrodes from residual gas and as the vessel is under the pull of the pump, said gases are thereby removed.

My invention provides a means of heating said electrodes under a very low vacuum, provides greater heat and speedier exhaust as well as vaporization of "getters", all under low vacuum with large quantities of gas present. It has the advantage of giving a vehicle of gas to carry out the freed gases, of heating any and all electrodes, whether or not they happen to be shielded from eddy currents, with maximum speed.

In the accompanying drawing Figure 1 illustrates a tube such as is contemplated by my prior Patent No. 1,558,111, dated October 20, 1925, and Figure 2 is a graph showing the steps involved in carrying out my present invention.

Following is a description of my process: The vessel or tube will be supposed to have three electrodes, such as the common three electrode vacuum tube. A tube such as is illustrated in the accompanying drawing may be prepared in accordance with my present invention and, in fact, all other vessels with two or more electrodes may be treated in the same way. The vessel is heated, before exhausting, to the maximum temperature which the container can stand; in other words, "baked out". It is then attached to the pumps, which consist of a rotary preliminary pump and an ordinary rotary molecular oil-filled vacuum pump as a final.

The vessel is brought up to a vacuum whereby the filament may be burned in safety, and then the vacuum is at once dropped back to the preliminary. High frequency oscillations generated by any of the well-known means are then passed between the grid or control electrode and the anode. The space between the electrodes becomes ionized and the electrodes immediately be-

come red-hot by impact of the gas ions. The "getter", which was attached to the electrodes, then becomes vaporized and deposited on the walls of the vessel.

As soon as the electrodes are sufficiently heated the current is turned off and the vessel is thrown onto the final pump, which pumps to its limit, and before the electrodes and the deposited film have had time to re-absorb any gas, the tube is tipped off. As the electrodes and the film cool they absorb gases from within the vessel and its vacuum steadily rises until the vessel becomes cold. This gives a vacuum much higher than that which could be obtained by the pump alone, as is well known in the art.

By an inspection of Figure 2 of the accompanying drawing, it will be seen that the tube is first evacuated to a high degree and that the filament is then burned in this vacuum. The reason for this high vacuum during the burning of the filament is because the filament will become damaged and possibly burn out unless a high degree of vacuum is maintained at this time. This operation thoroughly degasifies the filament. After this step the vacuum in the tube is allowed to fall to a low degree ranging from one to three millimeters in pressure. The grid and plate are then energized by circulating a high voltage or high frequency current between the two. The low vacuum during this operation facilitates the conduction of current through the gases in the tube and materially assists in heating the grid and plate by this method. During this period of my process, the grid and plate obtain a very high temperature which drives out the gases therefrom and also volatilizes the getters applied thereto. This operation is carried on for approximately twenty seconds and then the tube is again evacuated to the maximum degree possible by the pump and is then sealed off. It might be stated that after the tube is sealed off, the cooling of the grid and plate creates a further degree of vacuum and, as a result, a very satisfactory tube is produced.

I have found that if the preliminary burning and degasification of the filament is carried out as above, the damage to the filament is prevented when high frequency or high voltage current is passed between the other electrodes. This damage takes the form of pitting of the filament, due to the instant

ionization of the gas at the surface of the filament when the same has not been previously degasified.

The entire process of pumping, from the 5 time the vessel is attached to the pump until it is tipped off, is by my method less than two minutes, and the bulb is never allowed to cool down. No ovens or external heating devices are used.

10 It is quite natural that some leakage of the high frequency current should take place on the leads inside the tube and close to the pinch of the stem. This leakage heats the leads to the point that the glass of the stem 15 is apt to be heated so hot that it cracks, or becomes conductive and shorts as it becomes hot, with consequent loss of the vessel. My invention provides coating the leads and the inner part of the pinch with a heat resisting 20 non-conducting protection. This protection which consists of a cement, such as alundum cement, or other refractory material, absolutely prevents arcing or shorting between the leads, and confines the heating 25 effect where it belongs, on the electrodes.

My invention heats all electrodes evenly. When eddy currents are used to heat a cylinder with a grid inside, the cylinder takes all 30 the current and becomes hot, while the grid is shielded and does not become hot. My method heats both of them to a red or even a white heat if desired, with consequent greater freedom from residual gas. Furthermore, it is the inside electrode which is closest to the 35 filament and which, therefore, gets the hottest under normal operation of the tube, and is therefore apt to contaminate the tube with gas after it is made. My method heats the grid as hot as the other electrodes, much hotter than it will ever get under normal conditions again.

Having thus described my invention, what I claim and desire to secure by Letters Patent is—

1. The method of exhausting electrode 45 vacuum tubes or vessels, which consists of heating the electrodes and vaporizing "getters" under low vacuum only, thereafter pumping to the limit of a molecular pump, and sealing off before the heat of processing 50 has been lost.

2. The method of exhausting electrode vacuum tubes or vessels, which consists of heating the electrodes to free residual gas and vaporize "getters", thereafter stopping the 55 heating and pumping as high as possible to remove such gas and "getters" and to create a high vacuum, and sealing while the vessel is still hot.

3. The method of exhausting electrode 60 vacuum tubes or vessels, which consists of electrically heating all of the electrodes to a high heat by passing a current through certain of such electrodes before forming a high vacuum in the tube, thereafter stopping the 65 current and setting up a high vacuum to exhaust the tube, and finally sealing the tube while the electrodes are hot.

4. The method of exhausting a radio 70 vacuum tube having three electrodes therein, comprising a grid, a filament, and a plate, which consists of electrically heating all of the electrodes to a high heat by passing a current through the grid and plate before forming a high vacuum in the tube, the said grid 75 being heated to a temperature higher than it normally attains in use, thereafter stopping the current and setting up a high vacuum to exhaust the tube, and finally sealing the tube while the electrodes are hot.
